CLAIM

I claim, the ornamental design for a beverage capsule holder, as shown and described.

DESCRIPTION

FIG. 1 is a top perspective view of a beverage capsule holder showing my new design;

FIG. 2 is a bottom perspective view thereof;

FIG. 3 is a top plan view thereof;

FIG. 4 is a bottom plan view thereof; and,

FIG. 5 is a front elevation view thereof, the left side, right side and rear elevation views being identical.
